SELECTOR FOR ELECTRIC WIRING
SYSTEMS

Morten Balthazar Richter, Copenhagen, Denmark

Application August 17, 1937, Serial No. 159,571
In Denmark June 14, 1937

9 Claims. (Cl. 179—27.51)

For electric wiring systems, for instance automatic and semi-automatic telephone plants, it is known to use selectors with one or more rows of stationary line contacts, the said rows being arranged one above the other one in circular rows or parts of such rows, about the axis of rotation of a rotary supporting member for one or, more frequently, two sets of movable line contacts, which member is adapted to be rotated relatively to the said stationary contacts, and which sets of movable line contacts are disposed diametrically opposite one another on the said supporting member, which by its rotation moves the movable line contacts along the row of stationary line contacts and—when the stationary line contacts, for a desired connection across the selector, have been found by means of the searching contacts of the latter—will effect the desired connection by interconnecting, in pairs, the stationary line contacts concerned.

It is known to mount the movable line contacts slidably on the rotary supporting member in such a manner that when a coupling magnet, serving to couple the said member to a continuously driven driving shaft or driving disc, enters into operation, the movable contacts will be withdrawn radially from the stationary line contacts at the same time as, or immediately before, this coupling is effected, and consequently the movable contacts will not slide on the stationary contacts during the adjusting motion. Hereby the noise is avoided which the motion of the movable line contacts along the stationary line contacts would otherwise produce in the already effected connections across the same or other selectors in the selector-multiple concerned, and the advantage is attained that the wear on the contacts becomes small, and that no resistance against the motion of the rotary part of the selector will be produced by a co-operation between the movable and the stationary line contacts.

The coupling of the supporting member to the driving disc or shaft is ordinarily effected by one or, more frequently, two coupling shoes mounted adjustably on the supporting member and being adapted to be adjusted by the armature of the coupling magnet, when the latter is attracted, and to be withdrawn from the coupling position by springs, when the desired connection has been found, and the coupling magnet then automatically has been rendered currentless.

It is essentially important that the rotary motion of the selector should be stopped practically at once, when a desired connection across the

selector has been found by the searching contacts of the same.

Such an instantaneous stoppage of the rotary part of the selector has formerly been proposed to be produced by means of a ratchet wheel connected rigidly to the supporting member and one or more stopping pawls co-operating with the said wheel and being by means of springs moved into engagement with the ratchet wheel, when the coupling magnet becomes currentless.

The heretofore proposed selectors of this kind, however, suffer from the drawback that the ratchet mechanism will not with certainty stop the selector in the position found by the selector contacts, but allows the rotary part of the selector, which has a certain inertia, to continue its rotary motion so far, after the coupling magnet has released the coupling between the supporting member and the driving shaft or disc, that the selector will stop in the space between the found set of stationary line contacts and the following set of stationary line contacts, or possibly does not stop until it comes opposite the latter, viz. if the angular distance between adjacent stationary line contacts in the same row is small.

This is an essential drawback which certainly can be avoided either by constructing the selector with a relatively large play for the said further motion of the rotary part thereof, i. e., with relatively broad stationary line contacts and a considerable distance between the same, whereby, however, the number of line contacts to be disposed inside of a certain angular space in each row will be greatly reduced, or by fitting the selector with braking means for instantaneous stopping of the adjusting motion, when the coupling magnet becomes currentless. Such braking means, however, are unsuitable, as they constitute a relatively considerable resistance to the motion of the movable system of the selector, which is objectionable, as it is highly important that the adjusting motion of the selector should be effected as easily and as free of obstructions as possible.

The cause of a too late stopping of the rotary motion of the selector is to be looked for in the circumstance that the dead motion in the ratchet mechanisms used heretofore in selectors of the above mentioned kind is too great, i. e., that the angular motion performed by the ratchet wheel in the most unfavourable case, from the moment when the pawls have come into contact with the teeth thereof until the moment when one of the teeth engages one of the pawls—whereby the rotary motion of the ratchet wheel and, conse-

quently, of the selector is stopped—is greater than the permissible angular motion of the movable line contacts, after the desired connection has been found. Even if the said angular motion in the ratchet-wheel mechanism can be reduced by an increase in the number of ratchet-wheel teeth and the use of several mutually displaced pawls, there will nevertheless, owing to the size of the teeth, be a limit to the number of teeth that can be used, and owing to the circumstance that all the pawls should be able to be operated simultaneously by means of simple constructional devices there is a limit to the number of pawls that can be used.

15 The present invention has for its object to remove the said drawback in a different manner, viz. by constructing the ratchet wheel with a diameter of the same, or maybe a greater, order of magnitude as the diameter of circular path of the free ends of the movable line contacts, which is contrary to what has been the case heretofore, as the ratchet-wheel diameter heretofore, in view of the adjustment of the pawls relatively to the coupling shoes and the displacement of the movable contacts, has been made considerably smaller. According to the invention, the advantage is attained that the ratchet wheel can be fitted with such a great number of teeth that the magnitude of the angular motion 20 of the ratchet wheel and, consequently, of the rotary supporting member of the movable contacts, after the desired connection has been found, will be entirely irrelevant to the operation of the selector, provided that the pawl or pawls according to the invention is or are coupled in such a manner to the armature of the coupling magnet that the pawl or pawls will only be moved out of engagement with the ratchet wheel during the last short part of the attraction of the armature to the coupling magnet and, consequently, 25 will again be moved into engagement with the ratchet wheel—viz. by means of a spring or the like—during the first short part of the return motion of the armature, after a desired connection has been found, i. e., practically at the same moment as the coupling magnet has been rendered currentless.

30 The armature of the coupling magnet is returned from its withdrawn position by one or more springs constructed so powerful that the residual magnetism in the coupling magnet will not appreciably delay the return motion of the armature, after the same has been attracted. This spring may be the same as the spring that causes the pawl to engage the ratchet wheel.

35 As the ratchet wheel has a relatively considerable diameter, and the pawl must co-operate with the teeth on the periphery of the ratchet wheel, the coupling magnet is disposed entirely outside of the rotary part of the ratchet wheel, and in a preferred construction of the invention, the armature of the coupling magnet is coupled to the adjustable coupling shoes disposed on the rotary part of the selector and the movable line contacts disposed on the said part by means of a vertical rod disposed centrally in relation to the rotary part of the selector, the said rod being adapted to slide longitudinally, and one end thereof being connected to the armature of the coupling magnet, while the other end thereof co-operates with two levers pivoted to the rotary supporting member of the selector, the said levers being each connected to one of the coupling shoes disposed on the supporting member, and each to one of two supports for two sets of mov-

able line contacts, the said two supports being slidably mounted on two diametrically opposite sides of the supporting member, in such a manner that the said levers will be rotated by the said rod, when the armature is attracted, and thereby pulls the supports of the movable line contacts radially inward on the supporting member, at the same time as the coupling shoes are pushed radially outward so as to couple the said member to a continuously rotating driving disc. 10 The latter and the supporting member are mutually co-axial and are journalled mutually independently of one another on a common hollow stationary pivot pin, in which the said rod is adapted to slide.

15 The said two levers pivoted on the supporting member are preferably pivoted about horizontal axes, and may consist of two bell-crank levers, which are mutually linked together in such a manner that a motion of the one lever about its axis of rotation will produce a corresponding simultaneous motion of the other lever about the pivot axis of the latter and the two levers may further be interconnected by means of springs which, when the armature is released by the coupling magnet, will force these levers to rotate in such a manner that the coupling shoes are withdrawn from the coupling position, and the movable line contacts are pushed radially outward so as to touch the stationary line contacts after the same have been found.

20 The said pawl is suitably coupled to the armature of the coupling magnet by means of a lever with unequal arms, the shorter one of which is actuated by the said armature during the last part of the attraction motion of the latter, and thereby the longer arm will be caused to perform an angular motion suitable for withdrawing the pawl from the ratchet wheel, immediately before the armature, by its attraction, has caused the 25 coupling shoes on the supporting member to couple the latter to the driving disc. When the coupling magnet becomes currentless, the pawl will consequently during the first short part of the return motion of the armature from the 30 attracted position, i. e., practically at the moment when the coupling magnet becomes currentless, move into engagement with the ratchet wheel so as to stop the motion of the selector.

35 The said lever, which causes the pawl to be 40 adjusted may be fitted with a hook which enters into the path of the armature, if the stopping pawl is not in full engagement with the teeth on the ratchet wheel, and the latter therefore is in a position in which the movable line contacts come opposite the spaces between the stationary line contacts. In such a case the said hook will prevent the armature from moving so far backward that the movable line contacts can be moved out to the stationary line contacts and, thereby, can enter into the spaces between the latter, in which case the movable part of the selector would be unable to be set into operation by a fresh impulse.

45 The further details of the invention appear 50 from the following description of the construction of the same shown on the drawing.

55 Fig. 1 shows a longitudinal section of the selector,

60 Fig. 2 the same in top view, partly in section,

65 Figs. 3 and 4 the central part of the selector in side elevations, in two directions at right angles to one another.

70 In Fig. 1 is a continuously rotating driving disc, which is driven for instance by a driving

belt 2 consisting of a helical steel spring and journaled by means of a ball bearing 3, on a hollow vertical stationary post 4, Fig. 1, on which there is further journaled, by means of another ball bearing 50, a supporting member 5 for two radially slideable supports 7 disposed on diametrically opposite sides thereof, the said supports supporting two sets of movable line contacts 6, only one of which sets is shown in Fig. 1, while both sets are shown in Fig. 2. Each of these contact sets consists of three metal laminations which are wedge-shaped at their free end, and are disposed one above the other one on the plate-shaped support 7 which is made from electrically insulating material and is standing edge-wise, and is coupled by means of a pin 8, Fig. 1, to a lever 9, which is pivoted to the supporting member 5 and is further mentioned in the following.

In the construction shown, there are two such mainly plate-shaped levers 9 disposed in a vertical or approximately vertical position on diametrically opposite sides of the post 4, in such a manner that they rest with their lower edges 10 on the supporting member 5.

The post 4 is firmly held in the supporting base 11 of the selector on which several rows of stationary line contacts 12, Figs. 1 and 2, are disposed in circles about the axis of rotation A for the supporting member 5. In the construction shown, there are six rows of stationary line contacts disposed above one another and extending each over an angle of 180°, so that at any time either one or the other one of the two diametrically opposite sets of movable line contacts 6 will be situated within the angular space in which the stationary line contacts are provided.

The stationary line contacts 12 disposed in the various rows are interconnected in pairs by the movable line contacts 6, when the latter are adjusted to the line contacts concerned, viz. when a desired connection has been found. The searching is effected in known manner by means of two rows of stationary searching contacts 13, Fig. 1, and one or two movable searching contacts, not shown on the drawing, which co-operate with the stationary contacts, and are disposed on the supporting member 5 in such a manner that they slide in known manner along the contacts 13 during the adjusting motion of the selector, cf. my co-pending U. S. application No. 94,258, filed August 4, 1936, now Patent No. 2,135,015, dated November 1, 1938.

The movable line contacts are guided by pins 14 on the insulating supports 7. These pins extend through slits 15, Fig. 1, in the contacts 6, and between the inner end 51 of each of the latter and one of the pins 14 for instance, as shown, the inner one or, more suitably, the outer one of these, there is inserted a helical spring 16 maintaining the contacts 6 in resilient touch with the contacts 12, when a circuit connection across the selector has been established.

17 is a ratchet wheel rigidly attached to the rotatable member 5. 18 is a pawl engaging the ratchet wheel 17 and being pivotally mounted on the supporting base 11. The surface of the pawl 18 facing the ratchet wheel is fitted with a plurality of teeth, engaging a corresponding number of the teeth of the ratchet wheel. The pawl 18 is brought into engagement with the ratchet wheel 17 by means of a spring 19. 21, 25 is a two-armed lever pivoted about a pin 22 on the base 11. The said lever has a long arm 21 engaging one end of a rod 20, the other end of which is linked to the pawl 18, and a short arm

25, extending into the path of movement of the armature 23 of an electromagnet 24 mounted on the base 11, so that the said armature, when attracted by the electromagnet, will engage the said short arm and thereby cause the lever 23, 25 to move into the position shown in Fig. 1, thus causing the rod 21 to pull the pawl 18 out of engagement with the ratchet wheel 17, when the electromagnet 24 is energized for the purpose of intercoupling the driving disc 1 and the rotatable member 5 in the manner described below.

When the electromagnet 24 is thereafter de-energized—which occurs in a well-known manner, not described, when the searching contacts 13 of the selector have selected a desired circuit connection at the terminal 12 during the rotation of the member 5, the armature 23 is released by the electromagnet, and the spring 19 will then cause the pawl 18 to move into engagement with the ratchet wheel 17 in order to stop the rotary motion of the member 5. The rod 20 linked to the pawl 18 will, due to the action of the spring 19 upon the pawl 18, be forced to move longitudinally and will thereby turn the lever 21, 25 so as to cause the short arm 25 of same to shift 25 the armature 23 to the same short distance away from the electromagnet 24.

The armature 23 is shaped as, or supported by, a lever 27 which is pivoted about a pin 28 on the base 11 and is connected, at one end, to a vertical 30 rod 29 adapted to slide in the hollow post 4, the top end of the said rod being connected to a transverse member 30 the free ends of which support two downwardly directed pins 31. The latter rest each against the top side of one of two 35 flaps 32 projecting on two opposite sides of the post 4 from one of the levers 9. The said flaps 32, in combination with corresponding flaps 33, Figs. 2 and 3, on the other one of the levers 9, form link connections between the two levers 9, 40 in such a manner that the latter will be forced to rotate simultaneously from the positions shown by dotted lines 33' in Fig. 3 to the position shown by full lines in the same figure, when the flaps 33 are caused to rotate on account of the pins 31 acting thereon, viz. when the rod 29 is moved downward, in that the armature 23 is attracted towards the coupling magnet.

By this rotation of the levers 9, the latter are forced into the positions shown by full lines in 50 Figs. 1 and 3, where their upper ends rest against a transverse member 34 on the top of the post 4. As appearing from Fig. 1, the levers 9 have then withdrawn the contacts 6 so far, in a radial direction, from the stationary line contacts 12 55 that the contacts 6 will not touch the former. At the same time, two short arms 35, provided on each of the two levers 9 and projecting down through incisions 52 in the supporting member 5, have pushed two coupling shoes 36, Fig. 1, 60 disposed slidably on the supporting member 5, outward in a radial direction, so that the said shoes will come into contact with an annular flange 37 on the driving disc 1, in such a manner that the latter will take the supporting member 65 5 along during its rotary motion. The coupling shoes 36 are held in position and guided on the supporting member in any suitable known manner, for instance by means of screws 39 which pass through slits 40 in the coupling shoes. 70

Between the short arms 35 of the levers 9, springs 26, Fig. 3, are inserted on both sides of the supporting member and when the armature 23 is released from the coupling magnet the said springs will turn the upper ends of levers 9 away 75

from the transverse member 34, into the positions 9' shown by dotted lines in Fig. 3, and thereby the levers 9 will push the supports 7 radially outward, in such a manner that each 5 of the movable contacts 6; that at the given moment are situated within the arch in which the stationary line contacts are located, will be moved towards two of the said stationary contacts, and will establish the desired contact. At 10 the same time the levers 9 will pull the coupling shoes 36 away from the flange 37 of the driving disc. The springs 26 act by way of the flaps 33 on the pins 31, and push the latter and the rod 30 upward, as soon as the armature is released 15 from the coupling magnet.

During the first short part of the return motion of the armature, the pawl is brought into operation by the spring 19, at the same time as, or immediately after the coupling shoes 36 20 have been withdrawn by the springs 26 from the flange 37 of the driving disc, and not until then, during the continued motion of the armature, the springs 26 will move the levers 9, in such a manner that the contacts 6 will be caused 25 to touch the contacts 12.

When the coupling magnet again receives current, the armature will be attracted, and will then in the first place cause the contacts 6 to be withdrawn radially from the contacts 12, before 30 the coupling shoes, owing to the action of the armature, are moved out into the coupling position, as shown in Fig. 1, at the same time as, or immediately after, the armature has moved the pawl 18 out of engagement with the 35 ratchet wheel 17.

The pawl 18 is disposed in such a manner, relatively to the stationary line contacts, that it will always stop the movable line contacts 6 in a position radially opposite one or another 40 of the stationary line contacts, when the pawl reaches the bottom of the tooth spaces in the ratchet wheel, and the pitch of the latter can easily be made as small as required in view of the selector having to be stopped just at the set 45 of stationary line contacts that has been found at the given moment. It may happen, however, that the pawl, for some reason or other, does not slide home in the tooth spaces, but comes to rest 50 against the side faces of a tooth or two and, thereby, stops the supporting member 5 in an intermediate position in which the movable contacts 6 come opposite the space between two consecutive stationary line contacts. In order 55 to prevent the contacts 6 from their moving out into these spaces, whereby the movable part of the selector would become unable to enter into operation at a subsequent starting impulse, the lever 21 may be fitted with a hook 53 which, in the case of the pawl 18 having not reached 60 the bottom of the tooth spaces of the ratchet wheel, will extend down into the path of the armature 23, or rather the path of a pawl 55 attached adjustably thereto by means of screws 54, and will thereby prevent the armature from 65 returning so far from an attracted state that the contacts 6 can be moved out so as to touch the contacts 12.

Having now particularly described and ascertained the nature of my invention and in what 70 manner the same is to be performed I declare that what I claim is:

1. A selector of the power driven type for electric connecting systems, comprising a plurality of stationary terminals arranged in a number of 75 circular arcs, a rotatable member centrally dis-

posed relatively to the said arcs, a driving member to be continuously rotated, coupling means mounted on said rotatable member and adapted to intercouple the latter and the driving member, a number of movable contacts, adjustably mounted on the said rotatable member so as to be moved by same in circular paths along the said arcs of stationary terminals, a stationarily disposed electromagnet, an armature for said electromagnet, associated with the said coupling 10 means, and with the said movable contact so as to cause the coupling means to engage the driving member and to simultaneously shift the movable contacts radially out of engagement with the stationary terminals, when the said electromagnet is energized, a ratchet wheel firmly connected to the said rotatable member and being co-axial to same, a pawl co-operating with the said ratchet wheel, a lever engaging the said pawl and arranged to be engaged itself by the 20 said armature, when attracted, so as to move the pawl out of engagement with the ratchet wheel, before the armature due to its attraction causes the said coupling means to intercouple the said rotatable member and the said driven 25 member.

2. A selector of the power driven type for electric connecting systems, comprising a plurality of stationary terminals arranged in a number of circular arcs, a rotatable member centrally disposed relatively to the said arcs, a driving member to be continuously rotated, coupling means mounted on said rotatable member and adapted to intercouple the latter and the driving member, a number of movable contacts, 30 adjustably mounted on the said rotatable member so as to be moved by same in circular paths along the said arcs of stationary terminals, a stationary disposed electromagnet, an armature for said electromagnet, associated with the said coupling means and with the said movable contact so as to cause the coupling means to engage the driving member and to simultaneously shift the movable contacts radially out of engagement 35 with the stationary terminals, when the said electromagnet is energized, a ratchet wheel firmly connected to the said rotatable member and being co-axial to same, a pawl co-operating with the said ratchet wheel, a lever comprising a short arm arranged to be engaged by the said armature when attracted and a longer arm engaging the said pawl, so as to move the pawl out of engagement with the ratchet wheel during the last fraction of the total motion of said armature 45 when attracted, directly before the armature causes the intercoupling of the rotatable member and the driving member.

3. A selector of the power driven type for electric connecting systems, comprising a plurality of stationary terminals arranged in a number of circular arcs, a rotatable member centrally disposed relatively to the said arcs, a driving member to be continuously rotated, coupling means mounted on said rotatable member and adapted to intercouple the latter and the driving member, two sets of movable contacts, resiliently and slidably mounted on the said rotatable member so as to be moved by turns along the arcs of stationary terminals, a ratchet wheel, associated with the said rotatable member so as to be 60 rotated together with same, a pawl, a spring causing the said pawl to engage the said ratchet wheel so as to stop the rotation of same and of the rotatable member, a stationary mounted electromagnet, an armature for the said elec- 65 70 75 80 85 90 95 98

tromagnet, a lever journalled on a stationary base and associated with the said pawl and arranged to be engaged by the said armature so as to remove the said pawl from the ratchet wheel against the action of the said spring when attracted by the electromagnet, a vertically disposed rod, adjustably mounted in a central position relatively to the said rotatable member so as to be shifted longitudinally, means interconnecting the said armature and the said rod to shift the latter longitudinally in a downward direction, when the armature is attracted by the said electromagnet, two levers pivotally mounted on the rotatable member on opposite sides of the said centrally disposed rod so as to be engaged by same, when the rod is slid by the said armature, means for connecting each of said levers to one of said sets of movable contacts to shift the latter radially on the said rotatable member apart from the circular rows of stationary terminals, when the said levers are engaged by the said rod, and other means to connect the said two levers to the said coupling means, so as to cause the latter to intercouple the rotatable member and the continuously rotated driving member, simultaneously with the said radial displacement of the movable contacts.

4. A selector of the power driven type for electric connecting systems comprising a plurality of stationary terminals arranged in a number of circular arcs, a hollow stationary pivot pin centrally disposed relatively to the said arcs, a rotatable member pivotally mounted on the said pivot pin, a driven member pivotally mounted on the said pivot pin and adapted to be continuously rotated, means supported by the said rotatable member and adapted to intercouple this member and the said driven member, two sets of movable contacts, resiliently and slidably mounted on the said movable member so as to be moved by turns along the arcs of stationary terminals, a ratchet wheel, associated with said rotatable member, a pawl arranged to engage said ratchet wheel, a spring causing this engagement, an electromagnet, an armature for said electromagnet, a lever arranged to be engaged by the said armature, when attracted by the electromagnet, so as to cause the said pawl to move out of engagement with the said ratchet wheel against the action of the said spring, a vertical rod slidably mounted in the said hollow vertical pivot pin, means interconnecting the said armature and the said rod to shift the latter longitudinally in a downward direction, when the armature is attracted by the said electromagnet, an armature for said electromagnet, a lever arranged to be engaged by the said armature, when attracted by the electromagnet, so as to cause the said pawl to move out of engagement with the said ratchet wheel against the action of the said spring, a vertical rod slidably mounted in the said hollow vertical pivot pin, means interconnecting the said armature and the said rod to shift the latter longitudinally in a downward direction, when the armature is attracted by the said electromagnet, two levers pivotally mounted on the rotatable member on opposite sides of the said centrally disposed rod so as to be engaged by same when the rod is slid by the said armature, means for connecting each of said levers to one of said sets of movable contacts to shift the latter radially on the said rotatable member apart from the circular rows of stationary terminals, when the said levers are engaged by the said rod, and other means to connect the said two levers to the said coupling means so as to cause the latter to intercouple the rotatable member and the continuously driven member, simultaneously with the said radial displacement of the movable contacts.

5. A selector of the power driven type for electric connecting systems comprising a plurality of stationary terminals arranged in a number of circular arcs, a hollow stationary pivot pin centrally disposed relatively to the said arcs, a rotatable member pivotally mounted on the said pivot pin, a driven member pivotally mounted on the said pivot pin and adapted to be continuously rotated, means supported by the said rotatable member and adapted to intercouple this member and the said driven member, two sets of movable contacts, resiliently and slidably mounted on the said movable member so as to be moved by turns along the arcs of stationary terminals, a ratchet wheel, associated with said rotatable member, a pawl arranged to engage said ratchet wheel, a spring causing this engagement, an electromagnet, an armature for said electromagnet, a lever arranged to be engaged by the said armature, when attracted by the electromagnet, so as to cause the said pawl to move out of engagement with the said ratchet wheel against the action of the said spring, a vertical rod slidably mounted in the said hollow vertical pivot pin, means interconnecting the said armature and the said rod to shift the latter longitudinally in a downward direction, when the armature is attracted by the said electromagnet, two levers pivotally mounted on the rotatable member on opposite sides of the said centrally disposed rod so as to be engaged by same when the rod is slid by the said armature, means for connecting each of said levers to one of said sets of movable contacts to shift the latter radially on the said rotatable member apart from the circular rows of stationary terminals, when the said levers are engaged by the said rod, and other means to connect the said two levers to the said coupling means so as to cause the latter to intercouple the rotatable member and the continuously driven member, simultaneously with the said radial displacement of the movable contacts.

rotatable member pivotally mounted on the said pivot pin, a driven member pivotally mounted on the said pivot pin and adapted to be continuously rotated, means supported by the said rotatable member and adapted to intercouple this member and the said driven member, two sets of movable contacts, resiliently and slidably mounted on the said movable member so as to be moved by turns along the arcs of stationary terminals, a ratchet wheel, associated with said rotatable member, a pawl arranged to engage said ratchet wheel, a spring causing this engagement, an electromagnet, an armature for said electromagnet, a lever arranged to be engaged by the said armature, when attracted by the electromagnet, so as to cause the said pawl to move out of engagement with the said ratchet wheel against the action of the said spring, a vertical rod slidably mounted in the said hollow vertical pivot pin, means interconnecting the said armature and the said rod to shift the latter longitudinally in a downward direction, when the armature is attracted by the said electromagnet, two levers pivotally mounted on the rotatable member on opposite sides of the said centrally disposed rod and comprising each an edgewise disposed vertical plate supported freely at its lower edge upon the rotatable member and arranged to be engaged by the said rod, when the latter is slid by the said armature, means for connecting each of said levers to one of said sets of movable contacts to shift the latter radially on the said rotatable member apart from the circular rows of stationary terminals, when the said levers are engaged by the said rod, and other means to connect the said two levers to the said coupling means so as to cause the latter to intercouple the rotatable member and the continuously driven member, simultaneously with the said radial displacement of the movable contacts.

6. A selector according to claim 5 comprising springs interconnecting the downward extending portion of the lower portions of the two edgewise disposed levers on the rotatable member so as to swing the said two levers away from the positions into which they are brought by the action of the said rod, when the armature is released by the electromagnet, in order that one set of the movable contacts should engage the stationary terminals, and simultaneously putting the coupling means out of engagement with the driving member.

7. A selector of the power driven type for electric connecting systems comprising a plurality of stationary terminals arranged in a number of circular arcs, a hollow stationary pivot pin centrally disposed relatively to the said arcs, a rotatable member pivotally mounted on the said pivot pin, a driven member pivotally mounted on the said pivot pin and adapted to be continuously rotated, means supported by the said rotatable member and adapted to intercouple this member and the said driven member, two sets of movable contacts, resiliently and slidably mounted on the said movable member so as to be moved by turns along the arcs of stationary terminals, a ratchet wheel, associated with said rotatable member, a pawl arranged to engage said ratchet wheel, a spring causing this engagement, an electromagnet, an armature for said electromagnet, a lever arranged to be engaged by the said armature, when attracted by the electromagnet, so as to cause the said pawl to move out of engagement with the said ratchet wheel against the action of the said spring, a vertical rod slidably mounted in the said hollow vertical pivot pin, means interconnecting the said armature and the said rod to shift the latter longitudinally in a downward direction, when the armature is attracted by the said electromagnet, two levers pivotally mounted on the rotatable member on opposite sides of the said centrally disposed rod so as to be engaged by same when the rod is slid by the said armature, means for connecting each of said levers to one of said sets of movable contacts to shift the latter radially on the said rotatable member apart from the circular rows of stationary terminals, when the said levers are engaged by the said rod, and other means to connect the said two levers to the said coupling means so as to cause the latter to intercouple the rotatable member and the continuously driven member, simultaneously with the said radial displacement of the movable contacts.

wheel against the action of the said spring, a vertical rod slidably mounted in the said hollow vertical pivot pin, means interconnecting the said armature and the said rod to shift the latter longitudinally in a downward direction, when the armature is attracted by the said electromagnet, two levers pivotally mounted on the rotatable member on opposite sides of the said centrally disposed rod, a traverse member connected to the upper end of the said rod, a vertical, downwardly projecting pin on each end of said traverse member, the said two levers comprising each an edgewise disposed vertical plate freely supported at its lower edge upon the rotatable members and fitted with radially disposed arms arranged to be engaged by the said pins so as to cause the said two levers to swing when the centrally disposed rod is slid by the said armature, means for connecting each of said levers to one of said sets of movable contacts to shift the latter radially on the said rotatable member apart from the circular rows of stationary terminals, when the said levers are engaged by the said rod, and other means to connect the said two levers to the said coupling means so as to cause the latter to intercouple the rotatable member and the continuously driven member simultaneously with the said radial displacement of the movable contacts.

30 8. A selector according to claim 7 in which the two levers mounted on the rotatable member are interlinked.

9. A selector of the power driven type for electric connecting systems, comprising a plurality of stationary terminals arranged in a number of circular arcs, a rotatable member centrally disposed relatively to the said arcs, a

driving member to be continuously rotated, coupling means mounted on said rotatable member and adapted to intercouple the latter and the driving member, a number of movable contacts, adjustably mounted on the said rotatable member so as to be moved by same in circular paths along the said arcs of stationary terminals, a stationary disposed electromagnet, an armature for said electromagnet, associated with the said coupling means and with the said movable contact so as to cause the coupling means to engage the driving member and to simultaneously shift the movable contacts radially out of engagement with the stationary terminals, when the said electromagnet is energized, a ratchet wheel firmly connected to the said rotatable member and being coaxial to same, a pawl cooperating with the said ratchet wheel, a lever comprising a short arm arranged to be engaged by the said armature when attracted and a longer arm engaging the said pawl, so as to move the pawl out of engagement with the ratchet wheel during the last fraction of the total motion of the said armature when attracted, directly before the armature causes the intercoupling of the rotatable member and the driving member, and a hook on the said pawl arranged to extend into the path of the said armature of the said electromagnet, if the pawl is not in full engagement with the teeth of the ratchet wheel in order to prevent the armature from returning to a position, in which it allows the movable contacts to engage stationary terminals, until the pawl has moved in proper engagement with the ratchet wheel.
